UNITED STATES PATENT OFFICE

163,664

CARD PUNCH

Edward F. Wilson, Fairfield, Conn., assignor to
The Rock-Et Tool Company, Fairfield, Conn., a corporation of Connecticut

Application January 4, 1951, Serial No. 13,664

Term of patent 14 years

(Cl. D74—1)

To all whom it may concern:

Be it known that I, Edward F. Wilson, a citizen of the United States, residing at Fairfield, county of Fairfield, and State of Connecticut, have invented a new, original, and ornamental Design for a Card Punch, of which the following is a specification, reference being had to the accompanying drawing, forming part thereof.

Fig. 2 is a side elevational view thereof.

Fig. 3 is a plan view thereof.

I claim:

The ornamental design for a card punch, substantially as shown.

EDWARD F. WILSON.
